UNITED STATES PATENT OFFICE.

ANDREW SMITH, OF FRANKFORT, MICHIGAN, ASSIGNOR OF TWO-THIRDS
TO ALFRED V. FRIEDRICH, OF TRAVERSE CITY, MICHIGAN.

CLOTHES-PIN.

SPECIFICATION forming part of Letters Patent No. 749,234, dated January 12, 1904.

Application filed May 11, 1903. Serial No. 156,707. (No model.)

To all whom it may concern:

Be it known that I, ANDREW SMITH, a citizen of the United States, residing at Frankfort, in the county of Benzie and State of Michigan, 5 have invented certain new and useful Improvements in Clothes-Pins; and I do hereby declare the following to be a full, clear, and exact description of the invention, such as will enable others skilled in the art to which it appertains to make and use the same.

My invention relates to a novel construction in a clothes-pin, the object being to provide a device of this character which is more easily manufactured and requires less material and 15 is accordingly lighter and cheaper than the clothes-pins now generally used; and it consists in the features of construction hereinafter described and claimed.

In the accompanying drawings, illustrating 20 my invention, Figure 1 is a perspective view of a clothes-pin constructed in accordance with my invention. Fig. 2 is a transverse section of same on the line 2 2 of Fig. 1.

My said clothes-pin A is square in cross- 25 section and is provided at its upper end with a head B, which is likewise square in cross-section and has curved sides, the shank of the pin A being tapered at its upper end, as at C, to form the neck D. At its lower end said 30 shank is bifurcated by means of a recess E, extending diagonally through said lower end, said recess being of a width practically equal to the diagonal of said shank at its extreme lower end and gradually converging for about 35 one-third its length to a width slightly less than the diameter of the usual clothes-line and retaining said width to its end, said recess being about two-thirds the length of said shank.

My said pin is very easily and quickly made and requires very much less material than the 40 round clothes-pins generally used, the diagonal of my clothes-pin being equal or practically equal to the diameter of the round pin, so that the material saved is very considerable without materially affecting the strength of 45 the pin. This is due to the fact that the thickness of the prongs remains practically the same, as does also their width, so that the material saved is taken away only where it is not required. The flaring end of the recess is also 50 very wide, while the elasticity of the prongs is slightly greater than those of the round pins by reason of the less material contained therein.

The saving in material is also very advantageous in reducing cost of shipment by reason of reduced weight and volume, the latter being a great factor in reducing freights. By reason of the shape of my pins the same can 60 obviously be packed very much more closely than the round pins, the saving in space required being almost fifty per cent.

I claim as my invention—

As an improved article of manufacture, a clothes-pin square in cross-section and provided with a diagonal flaring recess, said clothes-pin having the characteristics hereinbefore set forth.

In testimony whereof I affix my signature in presence of two witnesses.

ANDREW SMITH.
